CLAIM

The ornamental design for a video image display for a portable phone, as shown and described.

DESCRIPTION

FIG. 1 is a perspective view of a video image display for a portable phone;

FIG. 2 is a front view of a video image display for a portable phone; and,

FIG. 3 is an enlarged front view of a video image display for a portable phone.

The broken line showing of unclaimed portions of a portable phone is included for the purpose of illustrating environmental structure and forms no part of the claimed design.

1 Claim, 3 Drawing Sheets

FIG. 1

FIG. 2
